UNITED STATES PATENT OFFICE.

HOWARD H. TALBOT, OF WOOSTER, OHIO, ASSIGNOR, BY MESNE ASSIGNMENTS, TO MACKINTOSH-HEMPHILL COMPANY, OF PITTSBURGH, PENNSYLVANIA, A CORPORATION OF PENNSYLVANIA.

VARIABLE-SPEED ROLLING-MILL DRIVE.

Application filed June 21, 1921. Serial No. 479,212.

To all whom it may concern:

Be it known that I, HOWARD H. TALBOT, a citizen of the United States, residing at Wooster, in the county of Wayne and State 5 of Ohio, have invented certain new and useful Improvements in Variable-Speed Rolling-Mill Drives, of which the following is a specification.

This invention relates to a rolling mill 10 drive for imparting driving power to the several stands of a continuous rolling mill for reducing metal. Heretofore, in continuous mills of this class it has been customary to drive the several rolls or stands 15 of the mill from a single line shaft through bevel or other gearing, connecting the line shaft with the individual roll shafts throughout. Because of the necessary successively increased speed of the several 20 stands from the first to the last pass, the variations between the gear ratios was necessarily excessive, and involved the use of extremely large and extremely small gears, as to their pitch diameter, together with the 25 necessary space, spacing of the rolls, variable and excessive friction, and other objectionable features.

In my present invention I overcome these 30 various objections by utilizing the power of a prime mover through the agency of two independent drive or line shafts, geared with the motor for different speeds, and connecting the several rolls of the entire number 35 of stands therewith in two independent series through corresponding series of pairs of bevel gears. These are suitably proportioned to transmit the desired speeds, and within entirely practicable limitations as to pitch diameter, with the resulting advantages, as hereinafter more fully described.

The invention is illustrated in the accompanying drawing in which Fig. 1 shows in diagrammatic plan view the several rolls of a continuous mill and the power and driving 45 mechanism therefor.

The power equipment of the mill utilizes two main driving shafts 2 and 3 respectively of relatively low and high speed, shaft 3 being connected with the driving motor 4 50 through its gear wheel 5 and pinion 6 of

shaft 7 connected directly with the motor, and arranged to transmit power to the finishing train of rolls through the interposed bevel gearing, at accelerating speeds. Shaft 2 is geared with the motor shaft through its 55 gear 8 and motor pinion 9.

Shaft 2 transmits power to the primary train of rolls through the interposed bevel gearing, at accelerating lower speeds, as will be readily understood by those familiar with 60 the art. Thus, shaft 2 is geared through pairs of bevels a, a' ; b, b' ; c, c' ; and d, d' , with the several drive shafts a^2, b^2, c^2 and d^2 of stands of rolls a^3, b^3, c^3 and d^3 of 65 the mill.

In a similar manner, shaft 3, of higher speed, transmits power to the secondary finishing train of rolls through the interposed bevel gearing at accelerating higher 70 speeds. This shaft 3 is geared through pairs of bevels e, e' ; f, f' ; g, g' and h, h' ; with the several drive shafts e^2, f^2, g^2 and h^2 of stands of rolls e^3, f^3, g^3 and h^3 of the mill.

Shaft 2 is preferably provided with a 75 thrust bearing A and shaft 3 with a thrust bearing B of suitable construction near the end portions of each shaft beyond the several gears thereof, and adapted to engage the shell of an adjacent pillow block bearing 80 10 and 10^a respectively. By this arrangement, shaft 2 is in tension relation to thrust bearing A and shaft 3 is in compression relation to thrust bearing B, and they 85 operate independently in each case to maintain their shafts and the gears thereof in continuous operative relation to the gears of the several roll shafts.

Referring to the power transmission from 90 motor 4 to shafts 3 and 2, it will be observed that the ratio of reduction from motor shaft 7 to shaft 3 through gears 6—5 is lower than through gears 9—8 to shaft 2. The relative driving speed of shaft 3 is therefore correspondingly greater than that of shaft 2, and approximates the same increased ratio as prevails between the average speed 95 of the series of rolls e^3, f^3, g^3, h^3 and that of rolls a^3, b^3, c^3, d^3 .

The stepped up pitch diameter of each 100

set of driving bevel pinions of each shaft 2 and 3, and of their companion driven bevel pinions, for each series, are thereby capable of ranges from a minimum to maximum for the driving pinions and from a maximum to minimum for the driven gears which are quite available within good practice as to pitch diameter and pitch line velocity. The use of the two main drive shafts 2 and 3, each receiving its power independently from the motor shaft, also provides for the adoption of the proper speeds for such shafts by selection of the proper ratios of their intervening gearing, so as to permit the use of driving and driven bevels having the characteristics noted. There is, therefore, present, in effect, a two-part drive equipment for the first and second series of rolls, each deriving its power from the same initial source.

The advantages resulting from this arrangement are several and important. It allows for the use of gears of a more uniform size and with better operating conditions as to bearing pressure and pitch line velocity than has heretofore been possible with the commonly used single driving shaft. Because of the arbitrarily selected speeds of the driving shafts 2 and 3, the ratios between the driven gears and driving pinions for each mill are materially reduced, thereby correspondingly reducing the distance between the roll centers of the several stands. This is of distinct advantage in shortening the length of the mill and making it more compact than would otherwise be possible, both as to the construction of the intervening guides and the decreased loss of heat in the metal in passing from one stand to another.

Due to the reduced variation between the diameters of the several pairs of gears, and the avoidance of excessively large or small gears, they are easily capable of being completely enclosed, providing absolute protection to the workman and facilitating ample lubrication. The use of excessively small pinions with relatively very large gears, resulting in excessive wear in the teeth of the pinion, is entirely avoided, with the consequent economy and better service.

These advantages will be appreciated by all those familiar with rolling mill practice. In a typical mill such as that shown, the speed of the motor shaft is 360 R. P. M.; of shaft 2, 45 R. P. M.; and of shaft 3, 120 R. P. M. The first stand of rolls a^3 is driven at a speed of 17 R. P. M. and the last stand, h^3 at 217 R. P. M., and the intermediate stands at uniformly increasing intermediate speeds, as for instance, b^3 24 R. P. M., c^3 37 R. P. M., d^3 51 R. P. M., e^3 81 R. P. M., f^3 116 R. P. M., and g^3 159 R. P. M. Such ratios may, of course, be changed or varied to suit the several reductions desired, de-

pendent on the design of the rolls or other conditions present.

The number of stands and their sets of gears may also be increased or decreased, or other changes or variations may be made from the specific construction shown and described by the designing engineer or builder to adapt the invention to different conditions or uses, but all such are to be understood as within the scope of the following claims.

What I claim is:

1. The combination with a continuous rolling mill utilizing successively operating rolls in two independent series, of a separate drive shaft geared with each series through corresponding series of gear reductions of different ratios, and a prime mover in driving connection with each drive shaft. 80

2. In a continuous mill for reducing metal, the combination with a prime mover, and two independent line shafts geared therewith, of successively reducing independent series of rolls geared with each shaft through gear reductions of different ratios. 85

3. In a continuous mill for reducing metal, the combination with a prime mover, and two independent line shafts geared therewith for variable speeds, of successively reducing independent series of rolls geared with each shaft through gear reductions of different ratios. 95

4. In a continuous mill for reducing metal, the combination with a prime mover, and two independent line shafts geared therewith for variable speeds, of a continuous successively operating series of primary rolls and pairs of gears of different ratios operatively connecting them with one line shaft, and a continuous successively operating series of secondary rolls and pairs of gears of different ratios operatively connecting them with the other line shaft. 100 105

5. In combination, a continuous rolling mill comprising a continuous primary and a secondary series of rolls, shafts therefor, a primary and a secondary drive shaft, series of pairs of gears of different ratios connecting the shafts of the primary roll series with the primary drive shaft, series of pairs of gears of different ratios connecting the shafts of the secondary series with the secondary drive shaft, and a prime mover geared with both drive shafts. 110 115 120

6. In combination, a continuous rolling mill comprising a continuous primary and a secondary series of rolls, shafts therefor, a primary and a secondary drive shaft of different speeds, series of pairs of gears of different ratios connecting the shafts of the primary roll series with the primary drive shaft, series of pairs of gears of different ratios connecting the shafts of the secondary series with the secondary drive shaft, and a 125 130

prime mover geared with both drive shafts. 7. In combination, a continuous rolling mill comprising a continuous primary and a secondary series of rolls, shafts therefor, a primary line shaft, a secondary line shaft of increased speed, a prime mover geared with the line shafts for driving the same at lower and higher speeds respectively, and gearing of different ratios connecting the shafts of the primary and secondary series 10 of rolls with the respective line shafts whereby to drive the successive stands of rolls at successively greater speeds, substantially as described.

In testimony whereof I hereunto affix my 15 signature.

HOWARD H. TALBOT.
